UNITED STATES PATENT OFFICE.

ELMER NICKERSON, OF OUTLOOK, MONTANA.

WRENCH.

Application filed March 5, 1925. Serial No. 13,317.

This invention relates to new and useful improvements in wrenches, and particularly to sliding jaw wrenches.

One object of the invention is to provide a wrench wherein the movable jaw has slideable and pivotal movement to more properly and firmly grip the work, and wherein such movable jaw will more quickly, and easily release itself from the work, for a new grip thereon.

Another object is to provide a moving means for the slideable jaw which is actuated by hand, against a spring means which also serves to move the jaw on its pivot, and maintain same in normal position.

Other objects and advantages will be apparent from the following description when taken in connection with the accompanying drawing.

In the drawing:

Figure 1 is a side elevation of a wrench made in accordance with my invention.

Figure 2 is a top plan view of the same.

Figure 3 is a sectional view on the line 25 3—3 of Figure 2.

Figure 4 is a bottom plan view of the jaw end of the wrench.

Referring particularly to the accompanying drawing, 10 represents the shank of the wrench, on one end of which is formed the stationary jaw 11. On the upper edge face of the shank, at a suitable distance from the fixed jaw 11, there are formed the ratchet teeth 12, and in the intermediate portion of the shank, slightly rearward of the toothed portion thereof, there is formed a longitudinal slot 13. Straddling the shank 10, and engaged therewith from the lower edge portion thereof, is the bifurcated portion 40 of the movable jaw 15, the forward end of which is toothed for cooperative action with the fixed jaw 11, on a piece of work. Disposed through the bifurcations of the movable jaw, and through said slot 13, is a pivot pin 16, on which the movable jaw is arranged to slide, within the limits of the slot, and on which said jaw is adapted for pivotal movement. Slidably embracing the shank 10, and the bifurcated portion of the jaw 15, is a block 17, and secured at one end within the portion of the block which lies below the shank 10, is the leaf spring 18, the other end of said spring being disposed longitudinally through the movable jaw, and being curved inwardly to bear against the adjacent edge face of the shank.

The normal action of the spring 18 is to swing the jaw 15 in a direction away from the lower or untoothed edge of the shank, by reason of the fact that said spring also bears on the movable jaw. Formed in the upper wall of the longitudinal opening of the block 17 are the ratchet teeth 19, which are arranged to interlock with the teeth 12, of the shank. The before-mentioned pivot pin 16 also passes through the block, whereby said block is capable of rocking movement to engage and disengage its teeth with relation to the teeth of the shank. Extending rearward from the upper portion of the block 17 is a fingerpiece 20, which, when engaged by the finger of the hand which grasps the shank 10, and pressed toward the shank, will cause the block to rock on its pivot, and the toothed end thereof rise so as to disengage its teeth from the teeth of the shank. The block and the movable jaw may then be moved longitudinally of the shank 10, within the limits of the slot 13, whereby to engage said jaw with one side of a piece of work.

It will be noted that the action of the spring 18 tends to rock the block 17 so that its teeth engage with the teeth of the shank, and at the same time cause the jaw 15 to be rocked away from the untoothed edge face of the shank.

After the block 17 has been rocked and the jaw 15 slipped into engagement with the work, the operator's finger is released from the fingerpiece, whereupon the block will resume its normal position, with its teeth engaged with the teeth of the shank, thereby holding the jaw 15 against the work. Upon rotating the wrench around the work, in the ordinary manner, the work will cause the jaw 15 to swing upwardly until it contacts with the shank, whereupon the teeth of the two jaws will bite into the work and permit the work to turn with the wrench. Upon turning the wrench in the opposite direction, the spring 18 will be permitted to swing the jaw 15 away from the shank, thereby releasing the hold thereof from the work, and permitting a new grip to be gained on the work.

What is claimed is:

1. A wrench including a toothed shank having an outer rigid jaw, an inner jaw having a bifurcation straddling the shank and being slidably and pivotally supported on the shank, a rockable bifurcated member

straddling the shank and the bifurcation of the jaw and arranged to interlock with the toothed shank, a pivot connecting the rockable member and bifurcated jaw and slideable in the shank, and a spring means carried by the rockable member and engaged with the shank and jaw for normally engaging the rockable member with the shank and urging the bifurcated jaw away from the shank.

2. A wrench including a shank having teeth and an outer rigid jaw, an inner jaw having a bifurcation slidably straddling the shank, the shank having a longitudinal slot, a bifurcated block straddling the bifurcation of the inner jaw, a pivot disposed through said slot and the bifurcations of the block and inner jaw, teeth on the block for engagement with the teeth of the shank, and a spring carried by the block and en-

gaging with the shank and with the inner jaw for normally urging the block into engagement with the shank and the inner jaw away from the shank.

3. A wrench including a shank, a jaw member slidably and pivotally mounted on the shank, a rockable locking member pivotally supported on the jaw member and interlockingly engaged with the shank, and a spring secured at one end to the rockable locking member and having its other end engaged with the shank while its intermediate portion engages with the jaw member whereby to simultaneously hold the jaw member yieldably away from the shank and the locking rockable member engaged with the shank.

In testimony whereof, I have affixed my signature.

ELMER NICKERSON.
